ATTORNEYS

UNITED STATES PATENT OFFICE.

JOSEPH PAUL BERGER, OF UVALDE, TEXAS.

WINDMILL ATTACHMENT.

Application filed October 17, 1922. Serial No. 595,141.

To all whom it may concern:

Be it known that I, JOSEPH P. BERGER, a citizen of the United States, and a resident of Uvalde, in the county of Uvalde and State 5 of Texas, have invented certain new and useful Improvements in Windmill Attachments, of which the following is a specification.

My invention relates generally to attachments for windmills, and it consists in the combinations, constructions and arrangements herein described and claimed.

More specifically, my invention is an attachment for windmills of the type of construction in which a so-called cut-off chain or cable is provided to automatically cut off or discontinue the driving connection between the wind wheel and the plunger of a pump with which the windmill is associated 20 when a sudden change takes place in the direction of the wind.

In windmills of the type of construction described the wind wheel and the rudder are ordinarily supported, so that the rudder is 25 mounted upon the said supporting means for independent rotation about a vertical axis, being also connected with the said supporting means through the agency of the so-called cut-off chain or cable which is attached at its ends to the rudder at spaced apart points and is trained about a plurality of spaced guide pulleys carried by the said supporting means. In strong winds, the cut-off chain or cable frequently disengages the 30 guide pulleys, thereby precluding the functioning of the cut-off chain to control the operation of the pump plunger in the manner described.

An object of the invention is to provide 40 an attachment embodying means for preventing the cut-off chain or cable from disengaging the guide pulleys without interfering in any way with the functioning of the cut-off chain and pulleys in an ordinary manner and in accomplishing the result for which provided.

A further object of my invention is to provide an attachment of the character described which is relatively simple in construction and is adapted to be operatively applied to a windmill of the class referred to without any change in the ordinary construction of the latter being required.

Other objects and advantages will be apparent from the following description, con-

sidered in conjunction with the accompanying drawings, in which:

Figure 1 is a fragmentary perspective view, showing a windmill equipped with my invention, only such parts of the windmill 60 being illustrated as are deemed essential to an understanding of the invention, and of the application thereof,

Figure 2 is a relatively enlarged perspective view, showing one of a pair of retaining guides included in the embodiment of the invention illustrated in Figure 1,

Figure 3 is a view similar to Figure 2, showing the other of the pair of retaining guides,

Figure 4 is a perspective view showing a third guiding and retaining element included in the device, and

Figure 5 is a perspective view showing in detached position a carrying frame included 75 in the windmill for supporting pulleys with which the aforesaid pair of guiding and retaining elements is associated.

Referring now to the drawings and particularly to Figure 1 thereof, I show a vertically disposed supporting column 1 supported by vertically spaced horizontal supporting plates 2 and 3 respectively, the said horizontal supporting plates being carried by a plurality of upstanding legs 4. The 80 supporting column 1 rests at its lower end in a socket 5 upon the horizontal supporting plate 3.

A collar 7 is secured upon the column 1 at the upper end of the latter, and is provided with oppositely extending bracket arms 8 and 9 respectively. The turn table 9^a of a rudder designated generally at 10 is pivotally supported at the outer end of the bracket arm 8 for rotation about a vertical 90 axis parallel with, but spaced from the vertical axis of the column 1. The rudder 10 also includes a vane 11 which is secured at its one end to the turn table 9 and is disposed substantially in a vertical plane.

A windwheel 12 is rotatably supported at the outer end of the bracket arm 9 for rotation about a horizontal axis.

A frame 13 having the form of a bar provided with pairs of spaced upstanding arms or forks 14—14 at opposite ends thereof, as best seen in Figure 3, is supported upon the collar 7 and carries a pair of pulleys 15 and 16 respectively, each of which is rotatably supported in notches 14^a—14^a 110

in the upper ends of the upstanding arms or forks 14—14 at an end of the frame 13. The pulleys 15 and 16 are mounted for rotation about horizontal axes. A third pulley 17 is 5 rotatably supported upon a horizontal shaft or stud 18 projecting laterally from the column 1 adjacent to the lower end of the latter. A cut-off chain or cable 19 is attached at its opposite ends to the turn table 10 9 at opposite sides of the latter and extends in a peripheral groove 20 in the turn table toward the upper end of the column 1, being trained about the pulleys 15 and 16 and extending downwardly in the column and 15 through apertures, (one of which is shown in Figure 1 at 21), in opposite sides of the latter into engagement with the pulley 17. One of the substantially vertically extending portions of the chain or cable is flexibly connected as at 21^a with a lug 21^b extending through the aperture 21 from a traveller 21^c which has a pair of outwardly extending lugs or radial extensions 21^d having notches 21^e in sliding engagement with vertical 20 guides 21^f. The traveller 21^c carries depending rods 21^g for connecting it with a suitable arrangement (not shown) for cutting off the driving connection between the wind-wheel and a pump plunger upon a determined vertical movement of the traveller. 25 The parts described so far are ordinary in construction and form no part of my invention except in so far as they cooperate with the parts which will now be described.

25 My invention provides a guiding and retaining element 22 associated with the pulley 16, a second guiding and retaining element 23 associated with the pulley 15 and a third guiding and retaining element 24 associated 30 with the pulley 17, whereby the cut-off chain or cable 19 will be effectually held against disengaging the pulleys without any interference with the rotation of the pulleys, or with the movement of the cut-off chain or cable while in engagement with the pulleys. 35 The guiding and retaining elements or members 22, 23 are identical in construction in essential respects, being adapted for positioning at opposite ends of the frame 13 as will presently appear, and therefore differing from each other in construction only in that one is a right hand member, while the other is a left hand member. It is therefore thought that the illustration of the guiding and retaining members 22 and 23 and the following detailed description of the former will suffice also to disclose the construction of the guiding and retaining member 23. Reference characters denoting portions of the member 22 have therefore been primed to designate corresponding portions of the member 23.

60 The element or member 22 comprises a plate portion 25 adapted to be inserted at the one end of the frame 13 between the latter

and a flange 26 which extends laterally of the upper edge of the collar 7 and with which the bracket arm 8 may be integral. A pair of upstanding ears 27—27 at the inner end of the flat plate portion 25 are adapted to straddle the frame 13 and are provided with alined bolt receiving openings 28 whereby these lugs may be clamped by means of a bolt 29 to the frame 13. As stated, the frame 13 supports the pulley 16 at one end thereof and the plate 25 is arranged substantially in underlying relation to the portion of the frame 13 supporting the pulley 16. An upstanding twisted extension 29 integral with the plate 25 is provided at its upper end with a tubular guide 30, which with the organization described, will be horizontally disposed and positioned between the pulley 16 and the proximate edge of the turn table 9^a. The tubular guide 30 is located at a level lower than that of the highest point on the periphery of the pulley 16. The portion of the cut-off chain or cable 19 extending from one side of the turn table over the pulley 16 will thus be held in engagement with the pulley 16 when threaded through the guide 30.

65 The plate 25 has an extension 31 depending from the side thereof opposite that provided with the extension 29. The extension 31 is provided with a vertical tubular guide 32 at its lower end. The extension 31 is preferably arcuate in cross sectional contour so as to conform substantially to the contour of the inner wall of the collar 7, and to thus permit of the positioning of the guide 32 close to the inner wall of the collar and out of the way of any part of the windmill which may be extended through the collar and through the column 1.

70 The guiding and retaining member 24 comprises a flat body which is substantially triangular in outline and is arranged in inverted position. The body 33 is provided with an opening 34 therethrough adjacent to its lower end, and this opening is adapted to the stud or shaft supporting the pulley 17. An attaching portion 35 at the upper end of the body 33 is provided with a plurality of openings 36 through which bolts 37 or the like may be projected into engagement with the column 1. The body 33 will thus be held in such relation to the pulley 17 that a pair of vertical tubular guides 38—38 provided at opposite sides of the body 33 in positions laterally offset therefrom are supported with their axes lying in a vertical plane extending through the pulley 17 intermediate of the sides of the latter.

75 From the foregoing description of the various parts of the device, the operation thereof may be readily understood. The guiding and retaining members 22—23 and 24 are secured in the positions described.

The cut-off chain or cable 19 is secured at one end to the rudder turn table 9 at one side of the latter and forwardly of the transverse median line of the latter. The 5 cut off chain or cable is then passed through the horizontal guide 30' of the guiding and retaining member 23, then over the pulley 15, downwardly through the vertical guide 32' of the guiding and retaining member 23, 10 then connected with the lug 21^a of the traveller 21^c, then extended downwardly through one of the guides 38, then about the pulley 17 and upwardly through the other guide 38, through the vertical guide 32 of the 15 guiding and retaining member 22, over the pulley 16, through the horizontal guide 30 of the guiding and retaining member 22, and is then attached at its end to the turn table 9^a at a point directly opposite that at 20 which the first named end is fastened to the turn table. When the rudder 10 turns on its axis independently of the column 1, as when a change in the direction of the wind takes place, the cut-off chain or cable is 25 permitted to move longitudinally in respect to the several guiding and retaining members and pulleys, but is prevented from disengaging the pulleys. The cut-off chain or cable is thus maintained continuously in 30 position to perform the function for which provided, that is, to effect such connection between the rudder and the means for rotatably supporting both the wind wheel and the rudder, as will result in automatic control of the means for cutting off driving force from the windwheel to a pump plunger.

Obviously, my invention is susceptible of embodiment in forms other than that illustrated herein, and I therefore consider as 40 my own all modifications and adaptations of the form of the device herein disclosed which fairly fall within the scope of the appended claims.

45 I claim:

1. In combination, a vertical column, bracket arms extending oppositely from the column adjacent to the upper end thereof, a rudder supported upon one of said bracket 50 arms for rotation about a vertical axis, the other of said bracket arms being adapted to rotatably support a windwheel, a pair of spaced pulleys supported at the upper end of the column for rotation about horizontal axes,

a third pulley rotatably supported on the 55 column at a lower level, a flexible chain or cable secured at its one end to the rudder at one side of the latter, and trained about said pulleys, being secured at its other end to said rudder at a point opposite that at 60 which the first named end is attached, and guiding and retaining members associated with said pulleys, there being a guiding and retaining member for each pulley, whereby the chain or cable is prevented from disengaging said pulley.

2. In combination, a vertical column, bracket arms extending oppositely from the column adjacent to the upper end thereof, a rudder supported upon one of said bracket 70 arms for rotation about a vertical axis, the other of said bracket arms being adapted to rotatably support a wind wheel, a pair of spaced pulleys supported at the upper end of the column for rotation about horizontal axes, a third pulley rotatably supported on the column at a lower level, a flexible chain or cable secured at its one end to the rudder at one side of the latter, and trained about said pulleys, being secured 75 at its other end to said rudder at a point opposite that at which the first named end is attached, a pair of auxiliary guiding and retaining members for said first named pulleys, each guiding and retaining member 80 comprising a flat plate adapted to underlie one of said pulleys, and having an attaching portion integral therewith, said plate having an upstanding extension carrying a 85 tubular guide through which the chain or cable may pass and having a depending extension also provided with a tubular guide through which the chain or cable may extend, said tubular guide being disposed at 90 different levels and at opposite sides of one 95 of said first named pulleys, and a guiding and retaining member for the third pulley, said last named guiding and retaining member comprising a vertically disposed flat body having attaching portion whereby it 100 can be attached to the column in juxtaposition to said third pulley, said flat body having a pair of vertical tubular guides at opposite sides thereof and being offset from the flat body so that their axes lie in a plane 105 passing through the third pulley intermediate of the ends of the latter.

JOSEPH PAUL BERGER.
